UNITED STATES PATENT OFFICE.

STEPHEN W. NELDNER, OF MILWAUKEE, WISCONSIN, ASSIGNOR TO THERESE M. NELDNER, OF MILWAUKEE, WISCONSIN.

ELECTRICAL TIME SWITCH.

Application filed February 4, 1926. Serial No. 85,917.

My invention relates to improvements in electrical time switches, and more particularly has reference to a switch of the class described adapted for use in an electrical circuit such as where it is desired to put out a light at a predetermined time, or otherwise control a circuit such as in cooking or the like.

Referring to the accompanying drawings, 10 Fig. 1 illustrates in perspective, parts being broken away, a suitable form of switch mechanism upon an enlarged scale, embodying an application of my invention. Fig. 2 is a longitudinal sectional view on the line 2—2 of 15 Fig. 1, and Fig. 3 illustrates the switch in convenient form with the outer shell applied and a suitable form of plug attachment.

4 indicates a block of fibre or other suitable insulating material, and 5 an angle plate 20 of brass or other suitable material suitably secured thereto, these parts forming the base or support of the mechanism. 6 and 7 indicate suitably stamped metal plates providing bearing for the pin or shaft 8. Referring 25 now more particularly to Fig. 2, this shaft it will be observed is provided with an enlarged portion 9 adapted to carry the coiled spring 10. Said shaft also has other enlarged portions 11, 12, and 13 and projects rearwardly 30 having a threaded end 14 provided with a knurled nut 15 and a lock-nut 16. The knurled nut 15 is provided with a circular flange 17 separating the concentric springs 18 and 19. These are compression springs which 35 serve to control a slip clutch arrangement, hereinafter described.

20 indicates a ring which also has a flange 21 separating the springs 18 and 19 and which has a transverse recess for the pin 22, which 40 passes through the shaft 8. 23 indicates a disc of mica between said ring 20 and another ring 24, and said ring 24 is recessed to receive the enlargement 13 of the shaft 8 and is also cut away as indicated at 25 to receive the tongue 45 or lip 26 projecting from the ratchet pinion 27. Another ratchet pinion substantially the same and mounted parallel therewith is indicated by the reference character 28 and that pinion also has an offset 29 projecting in the 50 opposite direction, said pinions both being loosely mounted upon the shaft 8.

30 and 31 indicate the legs of a knife switch which are adapted to rotate at their lower ends upon the shaft 8, the leg 31 having the 55 offset or projection 32 which is normally par-

allel with the offset or projection 29 from the pinion, the free ends of the spring 10 straddle opposite sides of these offsets or projections 29 and 32 so that when the knife switch, looking at Fig. 1, is moved clockwise, the offset 60 32 of the knife switch rides leftwardly away from the offset 29 of the wheel. 33 and 34 are offsets or lugs from the legs 6 and 7 respectively of the knife switch, pressed inwardly out of the same to come in the path 65 of the plunger racks hereinafter described. These plunger racks are the upper projections of the plungers 35 and 36 and are indicated by the reference characters 37 and 38' respectively. As the plunger 35 is pushed upwardly 70 looking at Fig. 1, the pinions 27 and 28 rotate clockwise, and in doing so depress the plunger 36 against the action of the spring 38, but the offset or lug 40 at the top of the rack 37 being in the path of the lip 34, prevents the end 75 of the spring 10 from throwing the knife switch rightwardly looking at Fig. 1, until after the lug 40 has risen sufficiently high to clear the offset 34. Then the knife switch flies rightwardly, looking at Fig. 1, under the 80 influence of the spring 10 the free ends of which have become distended or separated and are under tension. At the same time the offset or lug 41 of the rack 38' which extends in the opposite direction to the offset 40 of the 85 rack 37, is passing downwardly, and leg 30 of the knife switch having traveled rightwardly now presents its offset 33 in the path of the offset 41 which is trying to rise under influence of the compression spring 38, and 90 when it does rise sufficiently high, it clears the offset 33 and the knife switch then flies leftwardly, looking at Fig. 1, under the influence of the spring 10. 42, 43 are offsets or stops 95 projecting from the plate 7 to limit the throw of the knife switch as aforesaid.

Upon the outer end, the righthand end looking at Fig. 2, of the shaft 8, is mounted part of an ordinary watch movement without dial, hands, main spring, or setting devices. 100 The same is not shown for the reason that such mechanisms are well known in the art. The drive gear of the watch movement indicated by the reference character 44 is pinned to the shaft 8 as shown, and when the plunger 35 is pushed upwardly against the action of the compression spring 38 and the knife switch has moved rightwardly, looking at Fig. 1, the clock movement begins to operate 105 as soon as the finger is removed from the 110

plunger 35, the reason being as follows:— The compression spring 38 tending to drive the plunger 36 upwardly, also tends to rotate the sprocket gears 27, 28, and the sprocket gear 27 having the offset 26 engaging the ring 24 tends to turn the same, and the ring 24 being pressed against the disc 23 and ring 20 likewise tends to turn them, and the ring 20 being engaged by the pin 22 which passes through the shaft, tends to rotate the shaft through the frictional surface engagement described, thereby turning the main drive gear 44 of the watch movement referred to, and this operation continues until the compression spring 38 has expanded sufficiently to allow the offset 41 of the rack 38' to move up clear of the offset 33 when the knife switch flies leftwardly, looking at Fig. 1, and the watch movement stops until again energized by another thrust of the plunger 35.

45 indicates a clip suitably secured to the fibre block 4 as by the screw 46, and 47 indicates another clip suitably secured to the fibre block 4 as by the screw 48 said clips serving as contacts for the knife switch referred to, and 49 and 50 indicate screws beneath which the terminals of the electric circuit may be secured. In mounting the mechanism within the shell 51, 52, a screw 54 may be passed through the end of the shell into the lower portion 55 of the fibre block, and suitable side screws such as 56 and 57 may be passed through the sides of the upper shell 51 into the fibre block 4, the two halves of the shell being adapted to be screwed together as shown.

The coil springs 18 and 19 urge the disc 20 forcibly against the disc 24. These two discs, with the friction material 23 therebetween constitute a friction clutch. The clutch member 20 is fixed to the shaft 8 by the pin 22; while the companion clutch member 24 is loose on the shaft, but is coupled by the connection 26 to the pinion 27. The action of the clutch in the combination is as follows:—

When the plunger 35 is pushed upwardly or inwardly as above explained, the shaft 8 is rotated through the action of the rack bar 37 upon the pinion 27, connection 26, loose clutch member 24, and fixed clutch member 20. This rotary action in the shaft winds the spring of the clock-work 44 and puts the clock-work in a potential position in readiness for rotating the shaft 8 in an opposite direction through a given angular distance or number of revolutions in a predetermined time. The action of the clock-work mechanism when such predetermined time has elapsed is to open the switch mechanism as previously explained. However, it may become necessary or desirable to open the switch before this time period has expired and this is permitted by the use of the friction clutch 20, 24. By forcibly pressing upwardly or inwardly upon the plunger 36, the switch may

be opened without necessitating the rotation of the shaft 8, the shaft and its fixed clutch member 20 remaining stationary or moving only slowly with the clock-work 44; while the pinions moved by the plunger 36 and the connected loose clutch member 24 are shifted relatively to the shaft and fixed clutch member 20. The clutch may be subjected to any desired degree of tension by means of the adjusting nut 15.

Of course it will be understood that various modifications may be made in the construction and arrangement of parts without departing from the spirit of the invention as claimed.

I claim:

1. In a time switch of the class described, a main spindle having clock mechanism at one end, a knife switch adjacent thereto, and a slip clutch mechanism at the opposite end, a compression spring in combination with said switch, and a plunger for compressing the same, transmission between said compression spring and said clock mechanism for driving the same as said spring expands.

2. A time-switch comprising a shaft, a time-controlled mechanism connected to the shaft, a switch member having lugs pivoted on the shaft, pinions free on the shaft, overlapping projections on the switch member and one of the pinions, a switch-throwing spring on the shaft with its ends straddling said projections, a friction-clutch having one member fixed and one member loose on the shaft, a projection on the other pinion engaging said loose clutch member, plunger racks engaging the opposite sides of said pinions and having lugs disposed in the path of the lugs on the switch member except when the racks are in the innermost position.

3. A time-switch comprising a movable switch element, pinions rotatable relatively to the switch element, plunger racks for moving said pinions in opposite directions, a time-controlled mechanism coupled to move the pinions in one direction, overlapping relatively movable projections on the switch element and one of said pinions, switch opening and closing means positioned to be placed in a potential condition by the relative movement of said projections, and means for holding the switch element against opening or closing movement until the plunger racks have been shifted to a predetermined inner position.

4. A time switch comprising a movable switch element, a pinion rotatable relatively to the movement of the switch element, overlapping projections on said switch element and pinion, switch opening and closing means having engagement with the projections whereby to receive energy for operating the switch element when the projections are shifting relatively, and means for shifting said pinion back and forth and having parts

- cooperating with the switch element to prevent opening and closing movement thereof except when said pinion shifting means is at the limit of its inner movement.
- 5 5. A time-switch comprising a movable switch element, a pinion movable relatively to the switch element, means for shifting said pinion back and forth independently of the switch element while holding the switch element against movement except in one posi-
10 tion of said means, and a spring motor for shifting said switch element into open and closed positions and connected to be wound into potential position by the rotation of the pinion while the switch element is held stationary. 15

In testimony whereof I hereunto affix my signature.

STEPHEN W. NELDNER.
